[57] CLAIM

The ornamental design for an eyeglass frame assembly, as shown and described.

DESCRIPTION

FIG. 1 is a right front perspective view of an eyeglass frame assembly showing our new design;

FIG. 2 is a front elevational view of the eyeglass frame assembly of FIG. 1;

FIG. 3 is a rear elevational view of the eyeglass frame assembly of FIG. 1;

FIG. 4 is a top plan view of the eyeglass frame assembly of FIG. 1;

FIG. 5 is a left side elevational view of the eyeglass frame assembly of FIG. 1, which is a mirror image of the right side elevational view thereof;

FIG. 6 is a bottom plan view of the eyeglass frame assembly of FIG. 1;

FIG. 7 is a right front perspective view of a modified embodiment of the design shown in FIGS. 1-6; and,

FIG. 8 is a right front perspective view of the eyeglass frame assembly shown without the lenses for clarity of illustration only.
